UNITED STATES PATENT OFFICE.

WESLEY J. JOHNSON, OF DE KALB, ILLINOIS, ASSIGNOR TO STANDARD FOUNDRY & MFG. COMPANY, OF DE KALB, ILLINOIS, A CORPORATION OF ILLINOIS.

HOT-AIR-FURNACE CONSTRUCTION.

Application filed May 19, 1921. Serial No. 470,780.

To all whom it may concern:

Be it known that I, WESLEY J. JOHNSON, a citizen of the United States, residing at De Kalb, in the county of De Kalb and State of Illinois, have invented certain new and useful Improvements in Hot-Air-Furnace Constructions, of which the following is a specification.

This invention relates to hot air furnace construction, and especially to the construction and arrangement of the body portion or combustion chamber thereof. Among the objects of my invention is to provide a furnace body or combustion chamber of such shape and arrangement as to effect a thorough commingling and mixing together of the gases and produce substantially complete combustion thereof; further to so construct the combustion chamber that the gases as they move upwardly will be successively thrown inwardly in rotative movement, such movement increasing as the top is approached; further to so throw the gases back upon themselves that not only will they more thoroughly commingle and mix together, but their upward movement will be sufficiently retarded to prevent the escape of a large volume of unburned gases from the top of the combustion chamber; further to produce a simple, economical and efficacious combustion chamber for hot air furnaces; and such further objects, advantages and capabilities as will later more fully become apparent.

My invention further resides in the combination, construction and arrangement of parts illustrated in the accompanying drawings, and while I have shown therein a preferred embodiment, I desire the same to be understood as illustrative only, and not as limiting the scope of my invention.

In the drawings:—

Fig. 1 is an elevation of a furnace embodying my invention, parts of the casing walls and lining being broken away to show the interior parts in elevation.

Fig. 2 is a perspective view of a body portion or combustion chamber embodying my invention.

Fig. 3 is an enlarged plan view of Fig. 2, a portion of the fuel chute being broken away to conserve space.

Fig. 4 is a section on the line 4—4 of Fig. 3.

Referring to the drawings, and more particularly Fig. 1, my furnace is designated generally at A, and comprises the usual outer walls 1, and lining 2, spaced in the usual manner from the fire pot 3 and combustion chamber 4. Extending forwardly from the combustion chamber is the fuel chute 5, while as shown, the upper end of the combustion chamber connects with the radiator 5', from which the gases are conducted away in the usual manner through flue 6.

Since my invention resides primarily in the body portion or combustion chamber 4, the same will now be described in detail. This combustion chamber or body portion is formed at its lower edge with the flanges 7 and 8 to cooperate in the usual manner with the fire pot, to effect a joint therewith. The combustion chamber proper comprises the wall 9, converging upwardly towards its top 10, which latter is formed with the usual groove 11 to cooperate with the radiator 5' to form a joint therewith. As will be seen from Fig. 4, the wall 9 of the combustion chamber is of peculiar configuration, and as seen is formed with a plurality of circumferentially extending corrugations increasing in width towards the top. This provides a plurality of inwardly extending curved projections of successively increasing dimension, which function to cause the upwardly moving gases to be successively thrown in rotative movement toward the interior of the combustion chamber. The upwardly moving gases will first strike the curved ridge or projection 12, resulting in the gases being slightly thrown inwardly in rotative movement. As the gases continue upwardly their tendency for expansion will cause them to fill circumferential depression 13 (or in other words the valley of the corrugation), after which they will strike the inwardly curved ridge or projection 14, which projects inwardly a greater extent than ridge 12, and the gases will again be thrown inwardly with a rotative movement to a greater degree than in the case of their contact with ridge 12. Continuing upwardly the gases will be expanded or otherwise crowded into

the curved depression 15, and finally again thrown inwardly from the inwardly projecting ridge 16, which due to the greater width from ridge 14 to ridge 16, as compared with ridges 12 and 14, the rotative movement at this point will be greater than that described in connection with ridges 12 and 14, and will result in the greater portion of the gases being curled inwardly upon themselves in rotative movement, and thrown towards the center of the combustion chamber. From this it will be seen that the gases are thrown inwardly in rotative movement successively, which causes the gases to be thoroughly mixed to produce complete combustion. This movement also prevents the escape from the upper open end of the combustion chamber of a large quantity of unburned gases, and crowds and holds them within the combustion chamber much more completely than if the gases were permitted to merely ascend more or less uniformly from the bottom to the top of the combustion chamber.

Suitably spaced around the exterior of wall 9, are a plurality of ribs 17 increasing gradually in thickness toward the upper end as shown in Fig. 4, which not only strengthens the combustion chamber wall, but also functions to prevent injury from unequal expansion of the different parts of the wall.

This breaking up of the gases and causing them to curl inwardly in rotative movement a plurality of times during their movement upwardly through the combustion chamber, is a very important improvement over those types of combustion chamber in which the gases are curled inwardly only at the top, since as will be readily appreciated, there will be a much more thorough intermixing of the gases each time they are curled inwardly, and when this is done successively, the mixing of the gases and the combustion thereof is substantially complete before they leave the combustion chamber. It is also important to note the two short ribs 18 extending between the top of fuel chute 5 and the top of the combustion chamber.

Having now described my invention, I claim:

1. In furnace construction, upper and lower body members, said upper member having an open lower end portion, an upper end portion of smaller size than said lower end portion, and a wall connecting said end portions, said wall being formed with a series of undulations increasing in width upwardly and extending along a portion of the wall of said upper body member.

2. In furnace construction, a body member having an open lower end portion, an upper end portion of smaller size than in said lower end portion, a wall connecting said end portions, said wall being formed with a series of undulations extending along

a portion of said wall, said undulations increasing in width toward said upper end portion.

3. In furnace construction, a body member having an open lower end portion, an upper end portion of smaller size than said lower end portion, a wall connecting said end portions, said wall being formed with a series of undulations increasing in width upwardly and extending along a portion of said wall, and a plurality of circumferentially spaced upwardly extending ribs formed on the outer side of said wall and intersecting said undulations on said outer side.

4. In furnace construction, a body member having an open lower end portion, an upper end portion of smaller size than said lower end portion, a wall connecting said end portions, said wall being formed with a series of undulations increasing in width upwardly and extending along a portion of said wall, and a plurality of circumferentially spaced upwardly extending ribs formed on the outer side of said wall and intersecting said undulations on said outer side, said ribs increasing generally in thickness toward said upper end portion.

5. In furnace construction, a body member comprising an upwardly tapering wall having the upper portion thereof formed with undulations increasing in curvature toward the upper end of said wall, the uppermost undulation serving to direct upwardly moving gases inwardly and over on themselves to effect a substantially complete combustion thereof.

6. A combustion chamber for furnaces comprising an upwardly tapering corrugated wall portion, the corrugations thereof being substantially circumferential of the chamber and increasing in width toward the upper end of said chamber to set up a series of rotative movements in the gases as they progress upwardly.

7. A combustion chamber for furnaces comprising an upwardly tapering wall having the inner face of the upper portion of said wall formed with circumferential ridges and grooves increasing in width toward the upper end of said wall for giving the upwardly moving gases a rotative movement at each ridge and groove and for causing said gases to be successively thrown inwardly and back upon themselves to promote complete combustion of the gases.

8. A combustion chamber for furnaces comprising an upwardly tapering wall having the inner face of the upper portion of said wall formed with circumferential ridges and grooves increasing in width toward the upper end of said wall for giving the upwardly moving gases a rotative movement at each ridge and groove and for causing said gases to be successively thrown in-

wardly and back upon themselves to promote complete combustion of the gases, and upwardly extending ribs on the outside of said wall, said ribs increasing in thickness from the lower to the upper ends thereof.

9. A combustion chamber for furnaces comprising a wall converging upwardly and having a plurality of inwardly curved projections on its inner surface to cause the upwardly moving gases to be directed inwardly with rotative movements as the gases pass upwardly, the degree of such rotative movements increasing as the gases approach the top of the chamber, whereby a thorough commingling of the gases is effected.

10. In furnace construction, an upwardly tapering body portion formed with a series of substantially circumferential undulations progressively increasing in size toward the 20 tapered end of said body portion.

11. In furnace construction, a chamber

having a frusto-conoidal body portion provided with a series of substantially circumferential undulations progressing in size toward the apex of said body portion.

25

12. In furnace construction, an upwardly tapering body portion formed with variousized circumferential undulations and circumferentially spaced downwardly tapering ribs.

30

13. In a furnace construction, an upwardly tapering body portion formed with circumferential undulations increasing in width upwardly.

In witness whereof, I hereunto subscribe my name to this specification in the presence of two witnesses.

WESLEY J. JOHNSON.
